US0D1101583S

(12) **United States Design Patent** (10) **Patent No.:** **US D1,101,583 S**
(45) **Date of Patent:** **** Nov. 11, 2025**

(54) **TRACKING DEVICE MOUNT**

(71) Applicant: **ELEVATION LAB, INC.**, Portland, OR (US)

(72) Inventors: **Casey Hopkins**, Portland, OR (US); **Jacob Hull**, Portland, OR (US)

(73) Assignee: **Elevation Lab, Inc.**, Portland, OR (US)

(**) Term: **15 Years**

(21) Appl. No.: **29/937,714**

(22) Filed: **Apr. 16, 2024**

Related U.S. Application Data

(63) Continuation of application No. 29/883,595, filed on Jan. 31, 2023, now Pat. No. Des. 1,028,753, which is a continuation of application No. 29/855,866, filed on Oct. 7, 2022, now Pat. No. Des. 1,028,752.

(57) **CLAIM**

The ornamental design for a tracking device mount as shown and described.

DESCRIPTION

FIG. 1 is a top perspective view of a tracking device mount showing the new design;

FIG. 2 is a front view thereof;

FIG. 3 is a top view thereof;

FIG. 4 is a bottom view thereof; and,

FIG. 5 is a side view thereof.

The dashed lines shown in the drawings illustrate portions of the tracking device mount that form no part of the claimed design. The dash-dot lines shown in the drawings represent boundaries of the claimed design.

1 Claim, 5 Drawing Sheets
